[57] ABSTRACT

A process of mining a horizontal coal seam in an underground mine comprising first boring a hole in the middle of the seam while continuously removing the coal with an auger conveyor. Then after suitable penetration reaming wings on the conveyor are opened to span the full height of the seam. The wings have cutters on them so that as the apparatus is withdrawn the coal is broken and conveyed to the accessible face. The apparatus includes an advance mining head. A tubular enclosure for the conveyor carries the wings which are pivoted on longitudinally extending axes. A retracting movement of the shaft which drives the apparatus causes opening movement of the wings. Spiral ribs on the tubular enclosure engage the coal and urge the apparatus forwardly as it is rotated and resist rearward movement when the shaft is retracted. Doors between the wings and conveyor open to admit the cut coal into the conveyor and close to retain the coal on the conveyor. Flanges on the wings act to retain the coal. Rollers are carried by the wings to engage the coal and support the weight of the apparatus. Conveyor sections are attached to the shaft rearwardly of the reaming section. Propellers on the shaft and spiral vanes on the tubular enclosure form a transition conveying means between the reaming section and the rear conveyor sections.

**PROCESS AND APPARATUS FOR MINING BY RETREAT
REAMING**

BACKGROUND OF THE INVENTION

This invention relates to the underground mining of a generally horizontally extending coal seam by a boring and reaming process which minimizes dust propagation. The apparatus used in the process may also be used for earth boring and reaming operations of general application. More particularly the invention relates to the underground mining of coal by boring and reaming using an apparatus comprising a spiral or auger conveyor.

Auger mining of coal has been successful and economical in open pits and in hillsides where vertical clearance is available but it has not been used generally where head room is limited.

No art disclosing mining coal underground by boring and reaming has been found.

The U.S. Pat. to Kandle, No. 2,839,271, issued June 17, 1958 shows a tunneling machine comprising an auger which bores a horizontal hole through the earth from one location and then reams the hole by means of a reaming head fastened to the auger at a second location and then moved back to the first location.

Cannon et al., U.S. Pat. No. 3,220,494, issued Nov. 30, 1965 shows making a vertical hole from one gallery of a mine to another by drilling from an upper gallery to a lower one, then attaching a reaming head and reaming upwardly.

Forsyth, U.S. Pat. No. 3,280,416, issued Oct. 25, 1966 shows decoking a tower by drilling upwardly, then expanding reaming cutters in a space above the coke and reaming downwardly.

Wheeler et al., U.S. Pat. No. 732,479, issued June 30, 1903 shows an auger for forming a conical hole, the auger comprising pivoted end sections which are expanded to ream the hole.

Various other patents show reaming apparatus for enlarging the bore of a vertical drilled hole by reaming cutters which are expanded in the hole, and Shook, U.S. Pat. No. 2,847,189, issued Aug. 12, 1958 shows such an apparatus in which the hole is reamed by drawing the reaming cutters upwardly.

OBJECTS AND SUMMARY OF THE INVENTION

It is an object of the invention to provide for the mining of coal in underground mines with only a small amount of dust propagation.

It is another object to mine a seam of coal by forming a hole in said seam, enlarging the blind end of said hole to approximately the full height of said seam and breaking away the coal from the enlarged space towards the accessible face of the seam while conveying the coal towards said face.

Another object is to provide a reaming and boring tool and auger of spiral conveyor sections of small size whereby the mining operation may be carried out by a small number of men in a confined space.

Another object is to provide for mining coal whereby no men would work at the place where the coal is being removed from the seam and no roof bolting, props or rock dusting would be required at this locating.

Another object is to mine a seam of coal by using a cylindrical drilled hole having a diameter substantially equal to the height of the seam, the arch action of the walls of the drilled hole providing a roof and bottom support which allow mining under weak and tender rock which otherwise could not be mined conventionally.

In order to achieve these and other objects which will become apparent as the description proceeds I provide a drilling and reaming apparatus which may be used for drilling and reaming in the earth for various purposes but particularly for mining a horizontal seam of coal by boring a hole in said seam, conveying the bored coal to the accessible face of said seam by an auger or spiral conveyor, then reaming the blind end of the hole out by spreading reaming wings and continuing the reaming of the coal seam toward the accessible face while conveying the coal to said face with the auger or spiral con-

veyor. The apparatus comprises a spiral conveyor having the front end thereof enclosed by a cylinder, the front of the cylinder having cutting means and the wall of the cylinder having reaming wings pivoting on longitudinally extending pivot axes.

The apparatus is rotated by a shaft which is slidable through the center of the conveyor and connected by links to the reaming wings so that retraction of the shaft will open the wings. Doors on the cylindrical enclosure underneath the reaming wings open by gravity to allow the coal cut by the reaming wings to fall into the conveyor and then close to retain the coal on the conveyor. Spiral ribs on the cylinder engage the coal and urge the apparatus forwardly while the shaft is being rotated and retracted to open the reaming wings and ream the coal. Flanges on the wings retain the cut coal and direct it towards the conveyor. Propellers on the shaft and spiral vanes on the cylinder act as a transition conveyor between the reaming section and spiral conveyor sections attached to the shaft rearwardly of the reaming section.

BRIEF DESCRIPTION OF DRAWINGS

FIG. 1a is a side elevation of the rear of the apparatus in place in a mine shown in cross section;

FIG. 1b is a side elevation of the front of the apparatus in place in a coal seam with the reaming wings expanded;

FIG. 2 is a rear elevation of the apparatus;

FIG. 3 is a plan view of the driving means and cross conveyor with the spiral conveyor sections removed;

FIG. 4 is a side elevation of the front of the apparatus on a larger scale with the reaming wings retracted;

FIG. 5 is a view like FIG. 4 with the reaming wings expanded;

FIG. 6 is a front elevation of the boring head;

FIG. 7 is a cross section taken on the line 7-7 of FIG. 4 in the direction of the arrows;

FIG. 8 is a cross section on an enlarged scale taken on line 8-8 of FIG. 4 in the direction of the arrows;

FIG. 9 is a fragmentary cross section taken on line 9-9 of FIG. 4 in the direction of the arrows;

FIG. 10 is an elevation of FIG. 9 from the right;

FIG. 11 is a cross section taken on line 11-11 of FIG. 5 in the direction of the arrows;

FIG. 12 is a cross section on an enlarged scale taken on line 12-12 of FIG. 5 in the direction of the arrows;

FIG. 13 is a fragmentary section taken on line 13-13 of FIG. 12 in the direction of the arrows;

FIG. 14 is a cross section taken on line 14-14 of FIG. 4 in the direction of the arrows;

FIG. 15 is a cross section taken on line 15-15 of FIG. 5 in the direction of the arrows; and

FIG. 16 is a cross section taken on line 16-16 of FIG. 5 in the direction of the arrows.

DESCRIPTION OF THE INVENTION

The mining apparatus 1 of the invention comprises a driving unit 2, conveyor section 3, a reaming section 4 and an advance mining head or section 5. The apparatus is shown as being used in an underground coal mine for mining a seam 6 of coal by operations conducted from an entry 7 adjacent the accessible face 8 of the coal seam. Conventional bolts 9 are shown as providing supports for the roof of the entry.

The drive unit 2 is a conventional portable-type which may be set up in and readily moved to different locations in the entry 7. The unit 2 comprises a bed 10 carrying rollers 11 supporting a carriage 12 having channels 13 engaging the rollers, whereby the carriage may be moved back and forth over the rollers by an advance and retreat drive 14 comprising a power means 15 mounted on the carriage and driving a drum 16 on which is wound a cable 17 anchored at each end to the bed 10. Also mounted on carriage 12 is a power means 18 for rotating the boring apparatus by means of a driven shaft 19.

The driving unit 2 may be adjusted in elevation by hydraulically operated extensible and retractable legs or jacks 20.

A portable rack 21 is positioned adjacent the driving unit 2 and is adjustable in elevation as indicated by dotted lines by hydraulically operated legs or jacks 22. Additional spiral conveyor units 23 are stored on the rack in position to be attached to shaft 19 and spiral conveyor units 23 in the conveyor section of the boring apparatus.

A spiral conveyor unit 23 comprises a shaft 24 carrying a spiral blade 25 and connection means 26 at each end, as many units 23 are connected together as needed. The rearmost unit 23 is connected to driving shaft 19 and the foremost spiral conveyor unit is connected to shaft 27 which is square in cross section and is slidably received in bearings 28 secured in spiral blade 29. Spiral blade 29 is secured to and surrounded by a tubular cylindrical enclosure 30. Enclosure 30 has a rearward reaming section 31 and a forward or advance mining head or section 32. The rearward reaming section 31 is made of two thicknesses of metal, an outer shell 33 and an inner shell 34. The rearward section 31 is welded to the forward section 32 at their adjoining ends 35.

Four reaming wings 36 form segments of the outer shell 33 and are hinged thereto for pivoting about longitudinally extending axes by hinges 37. The reaming wings have rearward edges 38 which slope forwardly and outwardly when the wings are expanded or open and forward edges 39 which are parallel to the axis of the shaft 27. Replaceable cutters 40 are secured to the inner sides of the wings at the edges 38, 39. The cutters 40 are received in recesses 41 in enclosure 31 when the reaming wings 36 are in their closed positions.

In order to expand or contract the wings 36 arms 42 are pivoted to each wing and to the front of shaft 27 by universal joints 43. Thus, on relative rearward movement of shaft 27 with respect to enclosure 31 the wings will open and on relative forward movement of the shaft with respect to the enclosure they will close. A pin 44 secured to each wing 36 forms a pivot axis for the universal joint 43 associated with that wing. A roller 45 rotates on each pin 44. The roller bears against the coal and serves to support the apparatus. A ring 46 is secured to the inside of the forward end of enclosure section 31 to reinforce it, the ring spanning the spaces occupied by reaming segments or wings 36. Ring 46 comprises sectors 47 and 48 secured together so as to form pockets to receive the pins 44.

Forming segments of the inner shell 34 are doors 49 positioned inwardly of the wings 36 and between the flights of the spiral 29, as shown in FIG. 13. Doors 49 are freely pivoted on hinges 50 which extend longitudinally. The arrangement is such that as the apparatus rotates clockwise as viewed in FIGS. 8 and 12 the doors on the left and top open due to the effect of gravity and the doors on the right and bottom close. Thus coal scooped up by the reaming wings falls into the spiral conveyor through the open doors and is retained therein by the closed doors. Offset stops 51 are secured to the edges of the doors to cooperate with the inner shell to hold them in closed position. Flanges 52 on the inside of the reaming wings near the forward edge act to reinforce the wings and also direct the coal cut by the cutters 40 into the spiral conveyor 29.

Openings 53 are formed in enclosure 32 to provide for the passage of arms 42, it being noted that when arms 42 are operated to expand the wings they not only move outwardly radially but also move circumferentially due to pivoting of the wings on longitudinally extending axes. Suitable slots (not shown) are formed in the spiral conveyor 29 to provide for the passage of arms 42. Flanges 54 are secured at one corner of the openings 53 to reinforce the corner and act as a guide and stop for the extension arms 42, which bear against the flanges with considerable force as the apparatus is rotated.

Since shaft 27 slides with respect to spiral conveyor 29 and is fixed with respect to spiral conveyor sections 23 a gap between sections 23 and conveyor 29 develops when shaft 27 is retracted in order to open reaming wings 36 and pull the apparatus to the rear. In order to provide a transition conveying means between the conveyors 29 and 23 propellers 55 are secured to shaft 27 and spiral vanes 56 are secured to cylindrical enclosure 31.

Spiral rib 57 is provided on cylindrical enclosure 31 to the rear of reaming wings 36 and spiral rib 58 is provided on cylindrical enclosure 32 in front of wings 36 to engage the coal around the borehole and urge the apparatus forwardly when it is being rotated in the direction of the arrow 59 in FIGS. 11 and 12 and urge the apparatus rearwardly when it is rotated in the opposite direction.

The forward tapered end 60 of shaft 27 is received in a corresponding socket in an end stop 61 secured to spiral conveyor 29 to take the thrust of the shaft as boring proceeds in a forward direction. A ring 62 is secured to stop 61 and carries replaceable cutters 63. Other replaceable cutters 64 are secured to the leading edge of the enclosure 32 and to braces 65 connecting ring 62 and enclosure 32.

15 A cross conveyor 66 receives coal from spiral conveyor 23 and delivers it to a suitable point.

In operation the driving unit 2 is set up in the entry and the boring apparatus is driven into the coal seam 6 halfway between the top and bottom by attaching shaft 27 to shaft 19

20 and then rotating the shaft in the direction of arrow 59 by power means 18 while advancing the shaft by power means 15, the spiral ribs 57 and 58 engaging the coal and also acting to advance the apparatus. Cutter means 64 and 63 break the coal during this operation and spiral conveyor 29 conveys the mined coal back to the cross conveyor 66 which conveys it to a suitable destination. After boring proceeds a suitable distance the driving means 18 and shaft 19 are disconnected from conveyor shaft 27, retracted, then connected to shaft 24

25 of a conveyor unit 23, then advanced and thereafter disconnected, retracted, connected and advanced until the advance mining head formed by cutters 64, 63 and associated structure is driven as deep as possible into the coal seam. During this operation the rollers 45 act to guide and bear the weight of the apparatus to counteract the tendency of the head to drift downwardly.

When the desired penetration is reached the power means 15 is operated to retract the boring apparatus or cause it to retreat while rotation in the direction of arrow 59 is continued. Ribs 57 and 58 continue to urge the apparatus forwardly or resist movement rearwardly and therefore the wings 36 are expanded by arms 42. Actually, relative longitudinal movement between shaft 27 and tubular enclosure 30, on which the wings are carried, induced by urging the shaft and enclosure in opposite directions causes the wings to open regardless of whether only the shaft, the enclosure or both actually move in a longitudinal direction.

After wings 36 are expanded rotation of the apparatus in the direction of arrow 59 is continued and retraction or retreat of the apparatus is also continued until the desired amount of coal is mined. Conveyor units 23 are removed as retreat mining proceeds by manipulations similar to those used in advance mining. During retreat mining the coal is conveyed to face 8 by the spiral conveyors and delivered to cross conveyor 66 in the same manner as during advance mining. After mining is concluded at one location in the seam the driving unit 2 is moved laterally and the operation is successively repeated to mine out the seam.

While the wings 36 are being opened the rate of rotation is caused to be higher than after opening and during retreat mining. In other words, the ratio of rotation to retreat movement is caused to be higher during the opening of the wings than after the opening in order to effect the desired opening at a point as far inside the coal seam as possible. Completion of the opening operation is made known to the operator by a drop in power requirements.

The size of the apparatus, particularly the size of wings 36 and arms 42 is chosen so that the diameter of the initial hole will be about one-half or less than the height of the seam and the diameter of the enlarged hole will be about equal to the height of the seam. Ordinarily the entry would be about 16-feet wide and the length of conveyor units 23 and the head apparatus consisting of the reaming section and the advance mining section about ten feet each to enable easy handling of these sections or units and assembly and disassembly of the apparatus.

It will be noted that in this method of mining all operations are carried on at one underground location in the entry 7 at the face 8 of coal seam 6. Two locations, as suggested by the patents to Kandle and Cannon et al. are not needed. The breaking of the coal takes place in the interior of the seam so that dust propagation is minimized. Spiral rib 57 serves not only to affect movement of the apparatus but also acts as a stop to prevent transmission of dust outside of enclosure 31. Use of the reaming wings allows smaller units to be employed to mine the full height of the seam than would be possible in ordinary auger mining, thus allowing handling and assembly of the units in the restricted space of an underground mine. The curved, archlike nature of the walls of the hole produced by the apparatus provide better roof and bottom support than is provided when all the coal is cut away so mining under weak and tender rock is feasible which otherwise could not be mined conventionally.

The curved shape of each of the reaming wings 36 acts to direct the coal smoothly into the conveyor while the flange 52 on each wing inhibits the coal from escaping forwardly. The sloping rearward edges 38 of the wings facilitate retreat reaming and would cause collapse of the wings and prevent breakage if shaft 27 should be withdrawn faster than the coal is being mined. Doors 49 contribute to the efficient gathering of coal by automatically opening to admit coal to the spiral conveyor and closing to retain the coal in the conveyor.

If it should be desired to retract the reaming wings 36 and remove the apparatus a rotary movement in the reverse direction to that of arrow 59 would be imparted to the apparatus while shaft 27 would be given a forward movement. This would cause relative movement between the enclosure 31 and shaft 27 in a direction to collapse the wings. After the wings are collapsed the shaft 27 would be given a reverse or retreating movement while continuing rotation in a direction reverse to that of arrow 59.

It will be understood that the surface of the coal where it engages the apparatus is shown in somewhat of an idealized condition. Spiral ribs 57 and 58 engage or are embedded in the coal sufficiently to have a screwing action in either a forward or reverse direction depending on the direction of rotation but their engagement with the coal is also such that they may have longitudinal movement with respect thereto, which occurs during retreat mining when the rotation tends to cause a screwing action in an advancing direction but the actual movement of the apparatus is in a retreating direction.

I claim:

1. A process of underground mining of a seam of coal having a horizontal extension comprising forming a hole in said seam extending from an accessible face thereof to an interior portion, inserting cutting means into said hole from said accessible face, removing coal from said seam by said cutting means to enlarge the diameter of said hole at said interior portion, loading a conveying means extending into said interior portion with the coal removed by said cutting means, preventing the coal received by said conveying means from being unloaded into said interior region, conveying the coal to said accessible face and operating the cutting means to extend said interior portion of enlarged diameter towards said accessible face whereby substantially all the coal removed from the seam by the cutters is conveyed to the accessible face while said interior portion is being extended towards said accessible face.

2. The process of claim 1 in which said conveying means is a spiral conveyor and the coal removed by said cutter from the

seam falls onto the spiral flights of said conveyor.

3. The process of claim 2 in which the cutting means and the conveying means are part of a reaming tool having a boring head and the hole is formed by the boring head of the reaming tool.

4. The process of claim 3 in which the reaming tool has expandable reaming wings forming said cutting means and the forward portion of said conveyor is rotated by a shaft slideable with respect thereto, comprising urging the shaft in a rearward direction while urging the tool in a forward direction by spiral ribs engaging the wall of the hole to expand the wings.

5. The process of claim 4 in which the reaming tool has a tubular enclosure surrounding the forward portion of said spiral conveyor and carrying doors, comprising causing the coal removed by said cutters to fall through the open doors onto the conveyor and retaining the coal on the conveyor by closing said doors.

6. An earth-boring apparatus comprising a spiral conveyor having a continuous line of spiral flights, reaming wings mounted for expansion at the external perimeter of said spiral flights rearwardly from the front edge of said spiral flights, the forward portion of said spiral flights extending centrally and longitudinally with respect to said reaming wings.

7. An earth-boring apparatus as in claim 6 in which a tubular member is secured to and surrounds the forward portion of the spiral conveyor and said wings are mounted externally of said tubular member.

8. An earth-boring apparatus as in claim 7 in which a centrally located shaft rotates the forward portion of said spiral conveyor and is slideable with respect thereto and there are means attached to the wings and the shaft for expanding the wings on relative rearward movement of the shaft with respect to the tubular member.

9. An earth-boring apparatus as in claim 8 in which doors are located inwardly of the wings, between the wings and the conveyor, said doors opening to admit material cut by the wings into the conveyor and closing to retain material in the conveyor.

10. An earth-boring apparatus as in claim 9 in which spiral ribs on the tubular member are adapted to engage the earth surrounding the tubular member and urge the apparatus forwardly as the apparatus is rotated in a direction to cut the earth whereby rearward movement of the member is resisted as the shaft is urged rearwardly to expand the wings.

11. An earth-boring apparatus comprising a spiral conveyor having a forward portion and a rearward portion, said forward portion carrying expandable reaming wings, a shaft fixed to said rearward portion and longitudinally slideable in said forward portion, said shaft being rotatably driven by said rearward portion and rotatably driving said forward portion, and means attached to said wings and said shaft to expand said wings on the occurrence of relative longitudinal movement between said forward portion and said shaft.

12. An earth-boring apparatus as in claim 11 in which the wings are expanded by urging the shaft rearwardly, and including means engaging the earth for urging the wings forwardly.

13. An earth-boring apparatus as in claim 11 in which a tubular member surrounds the forward portion of said conveyor, the reaming wings are carried by said tubular member and the means engaging the earth comprise spiral ribs on the tubular member.
